TOW CLAMP FOR SKI POLE

James E. Gmeiner, 103 W. College Ave., Appleton, Wis.
Filed Apr. 4, 1958, Ser. No. 726,504
6 Claims. (Cl. 104—173)

This invention appertains to skiing and more particularly to a novel appliance for aiding a skier in the use of a tow rope.

It is common in most skiing localities to employ a tow rope for pulling skiers up mountainous and like slopes. Of necessity, the top rope must be tightly grasped by the skier. This causes undue hardship in that the skier's hand usually becomes cramped before reaching the top of the slope and the entire body of the skier is more or less under tension, and thus no helpful rest is given to the skier. It has been proposed to use clamps for engaging the rope, but this does not solve the entire problem.

It is one of the primary objects of my invention to provide means attached directly to or forming a part of one of the skier's poles for gripping the rope, and in such a manner that the pole will extend directly at a desired angle to the rope whereby the basket of the pole forms an effective seat for the skier, so that all strain is relieved from the skier and whereby the skier can assume a position of some repose.

Another salient object of my invention is the provision of means whereby the pole is used as a layer for operating the rope grip or clamp, so that when the pole is moved in one direction the clamp will tightly grip the rope and when the pole is moved in the opposite direction, the clamp will be released from the rope.

A further object of my invention is the provision of novel means for forming the clamp, so that the same can be quickly associated with the rope and one which will freely drop from the rope when pressure is relieved from the clamp.

A still further object of my invention is to provide a tow rope clamp carried directly by the pole, which will collapse to a position substantially parallel with the shaft of the pole, so that when the clamp is not in active use, the same can be disposed in an out-of-the-way position, whereby the pole can be effectively used without interference from the clamp.

With these and other objects in view, the invention consists in the novel construction, arrangement and formation of parts, as will be hereinafter more specifically described and claimed, and illustrated in the accompanying drawings, in which drawings,

FIGURE 1 is a perspective view showing my novel appliance in use;

FIGURE 2 is a detail fragmentary view looking down on the clamp and showing the same in its gripping position with the rope and attached to the shaft of a ski pole;

FIGURE 3 is a transverse sectional view taken on the line 3—3 of FIGURE 2, looking in the direction of the arrows;

FIGURE 4 is a fragmentary detail sectional view through the clamp and tow rope, the view showing the opposite side of the clamp from that shown in FIGURE 3;

FIGURE 5 is a fragmentary detail sectional view taken on the line 5—5 of FIGURE 2, looking in the direction of the arrows, illustrating the connection of the movable gripping jaw with the body portion of the appliance, and

FIGURE 6 is a view similar to FIGURE 2, but showing the clamp removed from the tow rope and in its collapsed, inoperative position alongside of the shaft of the pole.

Referring to the drawings in detail, wherein similar reference characters designate corresponding parts

2

throughout the several views, the latter C generally indicates my novel clamp for use in conjunction with a ski pole P for gripping engagement with a tow rope R.

The ski pole P is of a construction now in common use and hence includes a shaft 10 having a pointed lower terminal 11. The pole gradually increases slightly in diameter toward its upper end and the upper end carries the usual flexible handle loop 12. The pole adjacent to its lower pointed end is provided with the basket 13.

The clamp C includes an elongated body portion 14 which fits snugly around the shaft 10 of the pole P. This body portion 14 is in the nature of an open or split resilient sleeve, and the sleeve gradually tapers toward one end to conform to the configuration of the shaft of the pole. This sleeve on opposite sides of its open or split portion is provided adjacent to its opposite ends with apertured ears 15. Adjusting bolts 16 extend through the apertures of the ears and by tightening these bolts the sleeve can be firmly secured to the pole against accidental movement. In actual practice, the bolts 16 are removed from the ears 15 and the body portion 14 is spread open and sprung over the shaft 10 of the pole P, preferably adjacent to its lower end, but above the basket 13. The body portion 14 is then slid up on the pole to a point adjacent to the upper end of the pole and the bolts 16 are reinserted in the apertured ears 15 and tightened. The sleeve or body portion 14 at one side and adjacent to its opposite ends is provided with bearing ears 17 and 18. These bearing ears are arranged in longitudinal alignment for a purpose which will now appear. The lower bearing ears 17 pivotally support and carry a clamping arm 19. The outer end of the clamping arm 19 has formed thereon a jaw 20 and this jaw is in the nature of an open hook for partially embracing the tow rope R. It is to be noted that the hook opens out through its upper end, so that the same can be easily hooked onto the rope and so that the jaw can easily drop off of the rope by its own weight. The inner end of the arm 19 is connected to the lower bearing ears 17 by means of a pivot pin or rivet 21. Between the rigid jaw or hook 20 and the pivot pin 21, the arm is provided with a longitudinally extending guide slot 22.

Pivotal carried by the upper bearing ears 18 is a clamping arm 23 and the outer end of this arm is provided with an angularly extending U-shaped clamping jaw 24. This jaw slides back and forth over the jaw 20 and across the open end of the jaw 20. The inner end of the arm 23 is pivotally connected to the upper ears 18 by means of a pivot pin or rivet 25. In actual practice, one of the pivot pins 21 or 25 can be in the nature of an adjusting bolt for a purpose, which will be later set forth. The outer end of the arm 23 inward of the jaw 24 is provided with laterally extending guide ears 26 which slidably embrace the lower arm 19. These guide ears 26 carry a guide pin 27, which is slidably received within the slot 22.

With the clamp C attached to the pole P, as just described, and it is desired to connect the same with the tow rope R, then the rigid jaw 20 is hooked into engagement with the rope and the lower end of the pole P is swung outwardly away from the rope causing the pole to pivot on the pin 21 forcing the upper end of the pole toward the rope and the consequent sliding of the jaw 24 into intimate gripping contact with the rope. Thus the rope is firmly held between the rigid jaw 20 and the sliding jaw 24. Obviously, the greater the movement of the lower end of the pole away from the rope the tighter the gripping of the rope. As the clamp extends laterally from the rope R and at an angle to the rope the skier can easily pass the lower end of the pole between his legs and sit upon the basket 13. Thus an effective seat is provided for the skier and the pull of the rope is on the body of the

skier. Hence the firm grasping of the rope R by the skier is eliminated. If the skier should so desire, one hand could be used on the rope merely as a steadyng means.

The clamp C can be instantly detached from the rope and thus the device is provided with a maximum amount of safety for the skier. When it is desired to release the clamp C from the rope R, it is merely necessary for the skier to move the lower end of the pole toward the rope and this in turn will move the slideable jaw 24 away from the rope and out of gripping contact with the rope. As the rigid jaw 20 is in the form of an open hook, the same will fall off of the rope by its own weight.

When the ski pole P is being used in its normal fashion, the arm 22 is swung toward the pole P, as best shown in FIGURE 6 of the drawings, and hence the entire clamp will be disposed substantially parallel with the shaft 10 of the pole. Thus, the clamp is disposed in an out-of-the-way position and will not interfere with normal use of the pole.

As stated, one of the pivot pins 21 or 25 can be in the nature of an adjusting bolt and when the clamp is in its collapsed position, the bolt can be tightened so as to prevent accidental swinging movement of the inner and outer arms 19 and 23.

It is obvious that the shaft 10 of the pole itself could be manufactured with the lower and upper pivot ears 17 and 18, and hence the clamp can form a direct part of the pole. Obviously, in the form illustrated, the clamp is to be attached to poles now on the open market.

Various other changes in details may be made without departing from the spirit or the scope of this invention, but what I claim as new is:

1. A device for facilitating the pulling of skiers up inclines by tow ropes comprising a ski pole including a shaft, means carried by the shaft for releasably clamping a tow rope including, an arm having its inner end pivotally carried by the shaft, adjacent to the upper end of said pole, a hook-shaped rigid jaw carried by the outer end of said arm for partially receiving the tow rope, a second arm having its inner end pivotally carried by the shaft, in spaced relation to the first mentioned arm, a U-shaped jaw formed on the outer end of the second arm for movement toward and away from the hook-shaped rigid jaw for engaging the tow rope on the opposite side of the rope from said hook-shaped rigid jaw, said first mentioned arm being provided with a longitudinally extending guide slot, and said second arm having guide ears intermediate its length embracing the first mentioned arm, and a slide pin carried by the ears received in said slot, said U-shaped jaw being movable toward and away from the rigid jaw upon swinging movement of the shaft and said U-shaped jaw in one of its positions partially closing the hook-shaped rigid jaw.

2. In a device for facilitating the pulling of skiers up inclines by tow ropes, the combination with a tow rope, a ski pole including a shaft and a basket secured to the shaft adjacent to its lower end, and a releasable tow rope gripping clamp carried by the shaft adjacent to its upper end and in spaced relation to the basket, said clamp including an arm pivotally carried by the shaft and having a rigid jaw for partially encircling the tow rope and a second arm pivotally carried by the shaft having a clamping jaw slidably mounted on the first arm and operated by movement of one end of the shaft toward and away from

the rope and the rigid jaw, said sliding jaw being of a U-shape for partially encircling the rope on the opposite side thereof from the rigid jaw, and said sliding jaw being movable over the rigid jaw and the open portion of said rigid jaw by the swinging of the shaft with the shaft extending downwardly and away from the rope, whereby the shaft can be straddled by a skier with the basket in rear of the skier to form a seat.

3. A device for facilitating the pulling of skiers up inclines by tow ropes comprising a ski pole including a shaft, an arm pivotally carried by said shaft for swinging movement having a rigid jaw on its outer end for engaging one side of a tow rope, and a second arm pivotally carried by the shaft for swinging movement in spaced relation to the first mentioned arm and having a substantially U-shaped jaw on its outer end for partially engaging the tow rope on the opposite side thereof from the rigid jaw, and means slidably connecting the second arm adjacent to its outer end to the first mentioned arm.

10 4. A device for facilitating the pulling of skiers up inclines by tow ropes comprising a longitudinally split sleeve adapted to embrace a ski pole intermediate its longitudinal length and adjacent to the upper end thereof, means for tightening the split sleeve for gripping engagement with the ski pole, an arm pivotally secured to the sleeve adjacent to the lower end thereof for swinging movement having a longitudinally extending slot and a hook-shaped rigid jaw, a second arm pivotally connected to the sleeve adjacent to the upper end of said sleeve, a

15 U-shaped jaw carried by the outer end of said second arm, and said second arm having laterally extending guide ears embracing said first mentioned arm and a guide pin carried by said ears slidably received in said slot, said U-shaped jaw being slideable along said first mentioned arm upon swinging movement of the sleeve and pole.

20 5. A device for facilitating the pulling of skiers up inclines by tow ropes as defined in claim 4, and said arms being collapsible to an inoperative position substantially parallel with the sleeve.

25 6. A device for facilitating the pulling of skiers up inclines by tow ropes comprising a ski pole including a shaft and means carried by the shaft for releasably clamping a tow rope including a pair of arms pivotally carried by the shaft in spaced relation, a hook-shaped rope engaging jaw

30 formed on the outer end of one of said arms, a U-shaped jaw carried by the outer end of the other of said arms for movement toward and away from the hook-shaped jaw for engaging the opposite surface of a tow rope from the hook-shaped jaw, and means including a pin carried by the arm having the U-shaped jaw at a point intermediate its ends pivotally and slidably carried by the arm having the hook-shaped jaw, said arms being collapsible to an

35 inoperative position alongside of said shaft in substantially parallel relation therewith.

40 7. A device for facilitating the pulling of skiers up inclines by tow ropes comprising a ski pole including a shaft and means carried by the shaft for releasably clamping a tow rope including a pair of arms pivotally carried by the shaft in spaced relation, a hook-shaped rope engaging jaw

45 formed on the outer end of one of said arms, a U-shaped jaw carried by the outer end of the other of said arms for movement toward and away from the hook-shaped jaw for engaging the opposite surface of a tow rope from the hook-shaped jaw, and means including a pin carried by the arm having the U-shaped jaw at a point intermediate its ends pivotally and slidably carried by the arm having the hook-shaped jaw, said arms being collapsible to an

50 inoperative position alongside of said shaft in substantially parallel relation therewith.

45 8. A device for facilitating the pulling of skiers up inclines by tow ropes comprising a ski pole including a shaft and means carried by the shaft for releasably clamping a tow rope including a pair of arms pivotally carried by the shaft in spaced relation, a hook-shaped rope engaging jaw

55 formed on the outer end of one of said arms, a U-shaped jaw carried by the outer end of the other of said arms for movement toward and away from the hook-shaped jaw for engaging the opposite surface of a tow rope from the hook-shaped jaw, and means including a pin carried by the arm having the U-shaped jaw at a point intermediate its ends pivotally and slidably carried by the arm having the hook-shaped jaw, said arms being collapsible to an

50 inoperative position alongside of said shaft in substantially parallel relation therewith.
